(57)

CLAIM

The ornamental design for a wall mount for an audio device as shown and described.

DESCRIPTION

FIG. 1 is a front elevation view of a wall mount for an audio device, showing the new design.

FIG. 2 is rear elevation view thereof.

FIG. 3 is a top plan view thereof.

FIG. 4 is a bottom plan view thereof.

FIG. 5 is a right side view thereof.

FIG. 6 is a left side view thereof.

FIG. 7 is a first perspective view thereof; and,

FIG. 8 is a second perspective view thereof.

The features shown in broken lines form no part of the claimed design.

1 Claim, 8 Drawing Sheets
